DESIGN FOR A TABLE

August Hendrich, Franklin, Ind., assignor of three-eighths to Albert J. Welter, Franklin, Ind.

Application June 1, 1937, Serial No. 69,632

Term of patent 3½ years

To all whom it may concern:

Be it known that I, August Hendrich, a citizen of the United States and resident of Franklin, county of Johnson, and State of Indiana, have invented a new, original, and ornamental Design for a Table, of which the following is a specification, reference being had to the accompanying drawing, forming part thereof.

The figure is a perspective view of a table, showing my new design.

I claim:

The ornamental design for a table, as shown.

AUGUST HENDRICH.
